ABSTRACT

A self-adjusting fan vane of synthetic resin has a narrow, thickened, inflexible portion at the leading edge attached to the periphery of the fan hub and an elastically flexible vane flap attached to the inflexible vane portion and freely movable in respect thereto. A latticed insert is embedded in the vane, the insert having a first set of webs extending rectilinearly along a concave surface of the vane in a direction tangential to the periphery of the hub and a second set of webs extending in a direction radial to the hub, the webs of the second set being corrugated.

SELF-ADJUSTING FAN VANE

The present invention relates to improvements in fans for internal combustion engines.

Fans of this type are known wherein a plurality of vanes are attached to the periphery of a hub mounted for rotation about its axis. A narrow, thickened, inflexible vane portion at the leading edge of the vane is attached to the periphery of the hub and an elastically flexible vane flap is attached to the inflexible vane portion and is freely movable in respect thereto.

In the design of such fans, care must be taken that there is sufficient cooling of the engine at low rotary speed of the fan and at low engine speed. Such fans produce excessive and unneeded cooling at high and engine speeds. This unwanted cooling effect causes a considerable increase in the power requirements of the fan which must be met by the engine.

It has been attempted to avoid this disadvantage by designing the fan vane so that such power-determining properties of the vane as the angle of incidence and the radius of curvature of the vane change at higher rotary speeds under the influence of the air flow and centrifugal forces. While this influences the efficiency in dependence on the rotary speed, it does not influence it in dependence on the ambient temperature.

It has also been proposed to provide a laminated fan vane with layers of different coefficients of thermal expansion to cause changes in the angle of incidence and the curvature of the vane in dependence on the ambient temperature. This type of fan vane has the considerable disadvantage that the thermal expansion extends in all directions, causing unfavorable effects of the efficiency and increased fan noise. Also, the two layers, one of metal and the other of synthetic resin, are bonded together by an adhesive providing insufficient cohesion between the layers and eventually causing the vane layers to separate under the influence of the constant form changes. A further disadvantage of this type of vane is its high manufacturing cost because of the labor involved.

It is the primary object of this invention to overcome the above disadvantages of conventional fan vanes and to provide a vane which is self-adjusting by changing its form in dependence on the ambient temperature as well as the air flow and centrifugal forces to which the vanes are subjected during rotation of the fan.

The above and other objects are accomplished in accordance with the invention by embedding a latticed insert in a vane of synthetic resin. The insert has a first set of webs extending rectilinearly along a concave surface of the vane in a direction generally tangential to the periphery of the hub, and a second set of webs extending in a direction generally radial to the hub, the webs of the second set being corrugated. The corrugations of the webs of the second set extend in the direction of the other surface of the vane opposite to the concave surface thereof.

The insert may be of metal, for instance perforated sheet metal, a wire grid or an expanded metal sheet. It may also consist of glass fibre reinforced synthetic resin.

According to one preferred feature, a narrow beaded portion forms the trailing edge of the vane, and weights are embedded in the beaded portion.

The above and other objects, advantages and features of the present invention will become more apparent from the following detailed description of a now

preferred embodiment thereof, taken in conjunction with the accompanying drawing wherein

FIG. 1 is a partial front view of a fan according to this invention;

5 FIG. 2 is a fragmentary side view of the fan of FIG. 1;

FIG. 3 is a section along line III—III of FIG. 1;

FIG. 4 is a section along lines line IV—IV of FIG. 1;

FIGS. 5 and 6 are enlarged illustrations of the details 10 shown at V and VI, respectively, of FIGS. 3 and 4;

FIG. 7 is similar to FIG. 6, showing a modification of the corrugated insert web;

FIG. 8 illustrates an embodiment of an insert, in top view;

FIG. 9 is a section along lines IX—IX of FIG. 8; and

FIG. 10 is an end view of the insert of FIG. 8.

Referring now to the drawing and first to FIGS. 1 to 4, the illustrated fan comprises hub 1 mounted for rotation about its axis 10. A plurality of self-adjusting vanes

20 2 of synthetic resin are distributed about the periphery of the hub, either regularly or, if found desirable, irregularly spaced from each other. In operation, the fan rotates clockwise in the direction of arrow 4 so as to present a leading edge 5 and a trailing edge 9 to the incident air. A concave vane surface 17 and another surface 20 axially offset from the surface 17, extend between the leading and trailing edges of each vane.

The leading edge of the vane extends about perpendicularly to rotary axis 10 of the fan and about parallel

30 to a radius of the hub. The outer vane edge 7 extends about perpendicularly to the radius and is slightly curved, as shown, to connect with trailing edge 9 by way of a rounded corner 8. The trailing edge is about parallel to the leading edge 5. In a conventional manner, the vanes are so mounted on the hub that the angle of incidence of the air decreases outwardly in a radial direction.

40 A narrow, thickened, inflexible vane portion 11 attaches each vane to the periphery of the hub at the leading edge of the vane. The vane portion 11 is tapered in a radial direction, being narrower at the outer end than at the root. Thus, the wedge-shaped vane portion 11 has the flap 14 of the vane attached thereto along a line 12 which is inclined in respect of the radius, which assures good use of the centrifugal forces.

45 Flap 14 is elastically flexible and freely movable in respect of inflexible portion 11. Under the influence of air flow and centrifugal forces at increased rotary speeds of the fan, the flap 14 is flexed, thus changing the angle of incidence and the radius of curvature of the fan vane. The effect of the centrifugal forces is increased by providing a narrow beaded portion 15 at the trailing edge 9 of the vane, and by loading the beaded portion with weight means, such as balls or a weight 21.

50 The vanes 2 may consist of any suitable synthetic resin, such as polypropylene. As best shown in FIGS. 3 and 4, a lattice-shaped insert 3 is embedded in each vane. The coefficient of thermal expansion of the insert material is lower than that of the synthetic resin forming the vane. A useful insert material is metal but a synthetic resin reinforced with glass fibres may also be used.

55 The insert has a first set of webs 16 extending along concave surface 17 of the vane in parallel planes generally tangential to the periphery of hub 1. As shown in FIG. 1, the webs 16 extend across substantially the entire width of the vane 2. A second set of webs 18 con-

nect the webs 16 and extend in a direction generally radial to the hub. Sections of webs 18 between adjacent webs 16 are corrugated, the corrugations 19 thereof extending from webs 16 towards vane surface 20 and having axes of curvature extending in the common direction of elongation of webs 16.

In the embodiment shown in FIGS. 4 and 6, the corrugations 19 are about semi-cylindrical about axes of curvature parallel to the direction of elongation of webs 16 while the corrugations 19' in the modification of FIG. 7 are flattened and form a pinched neck portion. The latter modification provides a more secure connection of the insert with the vane since the corrugations 19' will more or less hook the webs 18 into the synthetic resin material of the vane when the insert is embedded therein.

A useful embodiment of an insert is illustrated in the various views of FIGS. 8 to 10. The specifically described and claimed web structure of the insert produces increased curving of vane 2 about the longitudinal axes of webs 16 with an increase in the ambient temperature since the thermal expansion coefficient of the synthetic resin material of the vane considerably exceeds that of webs 16. On the other hand, the synthetic resin material of the vane can expand independently of the lower thermal expansion coefficient of webs 19 in the direction thereof. Therefore, the vane will not be curved in this direction and will assume form 2' (FIG. 2). At lower temperatures and under the influence of the centrifugal forces, the vane will be flexed outwardly, as shown at 2" in FIG. 2.

Manufacture of the described vane is very simple. The insert 3 may be placed in an injection mold, with the webs 16 flush against the mold wall, and the synthetic resin is then injection molded about the insert to form the vane.

Since the insert webs 16 are flush with the surface of the vane, good heat conductivity is assured so that the vanes will adapt very quickly to temperature changes. Thus, the vanes of the present invention will operate at optimal efficiency since such power-determining factors as the angle of incidence and the curvature of the vane will change as a direct function of temperature changes as well as air flow and centrifugal forces. Furthermore, the manufacture of the vanes is very simple and a very good connection is provided between the insert and the vane.

What is claimed is:

1. In a fan for an internal combustion engine, in combination:

a. a hub having an axis of rotation and a periphery, and

b. a plurality of vanes extending radially from said periphery in spaced relationship, each vane including a leading edge portion attached to said hub and substantially inflexible, and a flap attached to said leading edge portion and more flexible than said edge portion, said flap including a trailing edge portion remote from said leading edge portion and having two axially offset surfaces connecting said edge portions, one of said surfaces being concavely arcuate about an axis of curvature approximately radial relative to said axis of rotation,

(1) said flap essentially consisting of synthetic resin composition and a lattice-shaped insert embedded in said composition, the insert being of a material having a coefficient of thermal expansion smaller than the coefficient of thermal expansion of said composition,

(2) said insert including two sets of webs, the webs of each set being elongated in a common direction, being transversely spaced from each other, and transversely intersecting the webs of the other set,

(3) the webs of one set being corrugated about axes of curvature extending in the direction of elongation of the webs of the other set, the webs of said other set being elongated in a direction from one of said edges toward the other edge.

2. In the fan of claim 1, the webs of the insert being of metal.

3. In the fan of claim 2, the insert consisting of perforated sheet metal.

4. In the fan of claim 2, the insert consisting of a wire grid.

5. In the fan of claim 2, the insert consisting of an expanded sheet metal.

6. In the fan of claim 1, the insert consisting of glass fibre reinforced synthetic resin.

7. In the fan of claim 1 said trailing edge portion being beaded, and weight means embedded in the beaded portion.

8. In the fan of claim 1, the webs of said one set having each a plurality of sections interposed between respective pairs of adjacent webs of the other set, said sections being corrugated.

9. In the fan of claim 8, said webs of said other set being substantially flush with said one surface, said corrugations projecting from the webs of said other set toward the other one of said two surfaces of said flap.

10. In the fan of claim 1, said sets being fixedly fastened to each other.
